DESIGN FOR A SPRAY HEAD

Jacques Stanitz, Warren, Ohio, assignor to
Mullins Manufacturing Corporation, Salem,
Ohio, a corporation of New York

Application September 26, 1945, Serial No. 122,352

Term of patent 7 years

(CL. D91—3)

To all whom it may concern:

Be it known that I, Jacques Stanitz, a citizen of the United States, residing at Warren, in the county of Trumbull and State of Ohio, have invented a new, original, and ornamental Design for a Spray Head, of which the following is a specification, reference being had to the accompanying drawing, forming part thereof.

Figure 1 is a plan view of a spray head showing my new design; Fig. 2 is a side elevation thereof; and Fig. 3 is a rear end elevation thereof.

I claim:

The ornamental design for a spray head, substantially as shown.

JACQUES STANITZ.
